UNITED STATES PATENT OFFICE.

FRANK P. LEONARD, OF TROY, NEW YORK, ASSIGNOR OF ONE-HALF TO FREDERICK C. CLAESSENS, OF TROY, NEW YORK.

NAIL.

Application filed January 25, 1923. Serial No. 614,900.

To all whom it may concern:

Be it known that I, FRANK P. LEONARD, a citizen of the United States, residing at Troy, in the county of Rensselaer and State of New York, have invented certain new and useful Improvements in Nails, of which the following is a specification.

This invention relates to improvements in nails or analogous fastening elements.

10. The primary object of this invention is the provision of a nail particularly well adapted for the securing of composition wall materials, such as plaster board, fiber board, wood board, and the like.
15. A further object of this invention is the provision of a fastening element embodying a novel head arrangement upon which a finishing surfacing may anchor, without liability of dropping therefrom incident to usual 20 shocks and vibrations.

A further object of this invention is the provision of a nail or analogous fastening element which is adapted to interlock with an article into which the same is driven, in 25 such manner as to prevent the same from working loose incident to ordinary shock and vibration.

Other objects and advantages of this invention will be apparent during the course 30 of the following detailed description.

In the accompanying drawing, forming a part of this specification, and wherein similar reference characters designate corresponding parts throughout the several views.

35. Figure 1 is a perspective view of the improved nail.

Figure 2 is a side elevation of the improved nail.

Figure 3 is a cross sectional view, taken 40 through a composition wall material, such as plaster board, showing the manner in which the same is secured upon studding or analogous foundation members, by means of the novel fastening nails.

45. In the drawing, wherein for the purpose of illustration is shown but the preferred embodiment of this invention, the letter A generally designates plaster, fiber, or analogous composition wall or board material, 50 which is adapted for attachment to studding or analogous framing B, as by means of the improved fastening elements or nails C.

It is well known to carpenters, plasterers, and others, skilled in building construction, 55 that composition board or wall material is

very difficult to maintain in secure and durable manner upon studding and analogous framing, primarily incident to the fact that nails which ordinarily fasten the same work loose either during the attachment of the 60 composition board or wall material, or incident to shocks or vibrations of the wall material which are placed upon the same when placing the trim, finishing coatings, or performing other like operations. Such 65 loosening of the ordinary fastening nail elements not only loosens the board material from the studding or framing, but also cracks the finishing coating upon the composition boarding or material, due to moving engagement of the head of the ordinary fastening nail therewith.

Referring to the construction of the improved fastening element C, the same includes a shank 10, preferably cylindrical, 75 and of any desired length, having the inserting end 11 thereof pointed, and having a relatively wide head 12 on the opposite end thereof.

The shank 10 is provided with a rib 15, 80 spiraled about the outer surface thereof, intermediate the pointed end 11 and head 12, for substantially one quarter of a turn about the shank. This rib 15 may be wedge shaped in cross section and the lower end 16 thereof 85 is preferably tapered into the outer surface of the shank 10, in spaced relation above the shank point 11. At the upper end of the spiral rib 15, the same provides a flat face 17, preferably disposed in a plane parallel 90 with the shank or axis thereof. Above the spiral rib 15 diametrically opposed barbs 20 and 21 are preferably provided, which may be polygonal in formation, and providing upper rather abrupt shoulders 23 in facing 95 relation toward the nail head 12. The lower rear surfaces of the barbs 20 and 21 may taper into the shank 10 in any approved manner. The barb 20 is preferably directly above the upper end of the spiral rib 15. 100 The barbs 20 and 21 each provide faces 29, which are preferably in the same plane with the face 17 of the spiral rib 15, facing in the same direction therewith. The upper abrupt shoulders 23 of the barbs 20 and 21 105 may taper gradually away from the faces 29, so that the nail may be readily driven, without undue restriction by the barbs and without liability of excessive mutilation of the fiber of the material in which the nail 110

is driven. It is to be noted that the spiral rib 15 is substantially midway of the barbs and the pointed end 11 of the shank 10, while the barb shoulders 23 themselves are spaced below the nail head 12 for a considerable distance.

The head 12 of the improved nail C is of novel formation, being particularly designed with the end in view of anchoring a finishing coating of material thereon. To this end, the head 12 is relatively wide, and is preferably provided with three flanges 31 upturned from the plane of the top surface of the head 12; said flanges 31 preferably being slightly arcuate over the top surface of the head 12, substantially as is illustrated in Figure 2 of the drawing.

The function of the nail in maintaining the composition wall material upon studding or other framing is illustrated in Figure 3 of the drawing. The nail upon being driven into the studding B is rotated, by engagement of the spiral rib 15 with the wood fibers, for substantially 90°, and after the barbs 20 and 21 have passed into the material of the stud B, the same will neatly cut the fiber of the wood, without unduly mutilating the same, and merely push the fibers back, so that said fibers will spring in closing relation over the shoulders 23 of the barbs 20 and 21, when the nail is entirely driven, as is illustrated in Figure 3. The head 12 of the nail may be slightly countersunk into the outer surface of the composition wall or board material A, substantially as is illustrated in Figure 3, and be retained in such countersunk relation incident to the effective locking function of the nail in the studding B. A coating of finishing material, such as plastering, varnishing, veneering, etc., may then be readily spread over

the head of the nail and anchored to the overturned flanges 31, as can be readily understood. Due to the fact that the nail is in secure locked relation to maintain the material A firmly against the studding B, there will be no liability of loose play of the nail head upon the composition material A.

The improved nail may be economically constructed in one operation, as by means of a dié, so that there are no features of the same which would make the cost of the same prohibitive.

Various changes in the shape, size, and arrangement of parts may be made to the form of invention herein shown and described, without departing from the spirit of the invention or the scope of the claims.

I claim:

1. As an article of manufacture, a nail having a shank portion, and a head portion, said head portion being relatively wide and having a plurality of flanges outturned from the plane of the top surface thereof, and arcuately bent to overlie said top surface.

2. As an article of manufacture, a securing member including a shank and head in rigid connection, the head having anchoring flanges extending from the side thereof opposite to said shank, said flanges being laterally overturned from the normal top surface of said head.

3. A nail comprising a shank, and a head rigid with the shank having marginal portions outturned from the plane of the top surface of said head at the opposite side of the head from said shank, said marginal outturned portions being bent inwardly in facing relation to overlie said top surface of the head.

FRANK P. LEONARD.
